UNITED STATES PATENT OFFICE

168,746

SANITARY HOLDER FOR BATHROOM
ACCESSORIES

Roy J. Laciura, Buffalo, N. Y.

Application April 26, 1952, Serial No. 19,489

Term of patent 14 years

(Cl. D4—3)

To all whom it may concern:

Be it known that I, Roy J. Laciura, a resident of Buffalo, New York, have invented a new, original, and ornamental Design for a Sanitary Holder for Bathroom Accessories, of which the following is a specification, reference being had to the accompanying drawing, forming a part thereof, and wherein:

Fig. 1 is a perspective view of a sanitary holder for bathroom accessories showing my new design;

Fig. 2 is a plan view thereof; and

Fig. 3 is a front elevational view thereof.

I claim:

The ornamental design for a sanitary holder for bathroom accessories, substantially as shown.

ROY J. LACIURA.
